(57) **CLAIM**

The ornamental design for a relay bus bar with built-in current sensor, as shown and described.

DESCRIPTION

FIG. 1 is a front perspective view of a relay bus bar with built-in current sensor, showing our new design;

FIG. 2 is a rear perspective view thereof;

FIG. 3 is a front view thereof;

FIG. 4 is a top plan view thereof;

FIG. 5 is a right side view thereof;

FIG. 6 is a left side view thereof;

FIG. 7 is a rear view thereof; and,

FIG. 8 is a bottom view thereof.

The broken line portion of the figure drawings is included to show unclaimed subject matter only and forms no part of the claimed design.

1 Claim, 8 Drawing Sheets
